E. Howell

United States Patent Office.

E. HOWELL, OF ASHTABULA, OHIO.

Letters Patent No. 96,809, dated November 16, 1869.

IMPROVEMENT IN HEMMER FOR SEWING-MACHINE.

The Schedule referred to in these Letters Patent and making part of the same

To all whom it may concern:

Be it known that I, E. HOWELL, of Ashtabula, in the county of Ashtabula, and State of Ohio, have invented certain new and useful Improvements in Hemmers for Sewing-Machines; and I do hereby declare that the following is a full and complete description of the same, reference being had to the accompanying drawings, making part of this specification, in which—

Figure 1 is a top view of the hemmer.

Figure 2, a view of the front end.

Figure 3, a view of the rear end.

Figure 4, a side view.

Figure 5, a view of a hemmer, to which reference will be made.

Figure 6, a view of the plate from which the hemmer is formed, all of which represent enlarged views.

Like letters of reference represent like parts in the different views.

This invention consists in the construction of a peculiar device that is attached to a sewing-machine, whereby the edge of a piece of cloth is turned or folded over to form a hem.

In fig. 1, A represents the folder or hemmer, which consists of a thin plate of metal, cut to the peculiar shape shown in fig. 6.

The limb B is folded backward over the central section of the plate, and again forward upon itself, forming an S-shape curvature C, as shown in fig. 2, which represents an end view of the hemmer.

The limb D is then bent upward and over upon the S-shape member B, thus embracing or covering said member, as shown in fig. 2, a side view of which is shown in fig. 4.

To the central section E, fig. 4, of the plate, is given a peculiar folding twisting curvature, which, as will be seen, brings the edge F over to and even with its opposite edge. Over, reversely, upon this, is bent the member G, as shown in figs. 4 and 1, which latter figure also shows the twisting curvature given to the central section of the plate. These peculiar curvatures and twistings given to the plate will, on inserting the edge of the cloth therein, and drawing the same through the entire length of the convolution of the hemmer, turn down the raw edge and tuck it under a second

fold, in the manner proper for a hem, neatly and evenly throughout the entire length of the cloth. Thus, one corner of the edge of the cloth is slightly curved, so that the raw edge will fit in the lower part of the curve C given to the member B. At the same time it is passed under the curve of the member D, as indicated by the dotted line a, fig. 2. This produces the first folding down of the raw edge upon the cloth.

Now, on drawing the cloth in and along toward the opposite end, the turned-down edge is folded under, in consequence of the peculiar twist given to the middle section of the plate, and completely turned or tucked in and pressed down by the member G, as the hem emerges from the hemmer at the end F, thereby completing the hem for the operation of the needle.

As the cloth is being drawn in, a slight tension is given to it, by the spring H, under which it is passed along, and is thereby not only prevented from puckering, but is also kept straight, and guided into the hemmer, which is secured to the table of the machine in advance of the needle, by the arm J, to which the hemmer is attached.

Fig. 5 represents a modification of fig. 1, the difference being that the member B is given but one curve, and substituting, for the second, a tongue, J, which facilitates the folding under of the raw edge of the cloth, in connection with the twist given to the middle of the hemmer at K.

Though this construction of the hemmer does very well, it is found, by experience, that the one above described is the best.

What I claim as my improvement, and desire to secure by Letters Patent, is—

The hemmer or folder A, when formed of the piece of metal B D E G, in the manner described, having tension-spring H and arm I, by which it is attached to the sewing-machine, all constructed and arranged to operate substantially in the manner and for the purpose described.

E. HOWELL.
